UNITED STATES PATENT OFFICE.

CARL SCHWARZ, OF CHARLOTTENBURG, NEAR BERLIN, GERMANY, ASSIGNOR TO
WESTINGHOUSE ELECTRIC & MANUFACTURING COMPANY, A CORPORATION OF
PENNSYLVANIA.

SAFETY ARRANGEMENT FOR ANTENNE.

Application filed October 31, 1921. Serial No. 511,834.

To all whom it may concern:

Be it known that I, CARL SCHWARZ, a subject of the German Republic, residing at Charlottenburg, near Berlin, Germany, have invented certain new and useful Improvements in Safety Arrangements for Antennæ, of which the following is a specification.

This invention relates to radio signaling and particularly to signaling by high-frequency currents impressed upon line conductors. It is particularly applicable to the transmission of radio signals over high-tension power conductors.

It is an object of this invention to prevent abrupt changes in potential or other disturbances upon the line wires from injuring the signaling apparatus.

It is a further object of this invention to provide a connection to ground, which shall conduct disturbing currents away, without interfering with the signaling currents.

It is a further object of this invention to arrange a plurality of antennæ symmetrically with respect to the ground connection so that disturbances impressed upon the antennæ shall neutralize one another.

Other objects of the invention and details of the construction will be apparent from the following description and the accompanying drawing, in which—

Figure 1 is a diagrammatic showing of the arrangement embodying this invention:

Fig. 2 illustrates a modification thereof;

Fig. 3 shows provision for tuning;

Fig. 4 shows a modification of the structure illustrated in Fig. 3;

Fig. 5 illustrates a further modification;

Fig. 6 shows the adaptation of the invention to the combined sending and receiving apparatus;

Fig. 7 illustrates the application of the invention shown in Fig. 6 to the three wires of a three-phase line, and

Fig. 8 shows a modification of the arrangement shown in Fig. 6.

The line *l* represents one of a plurality of line wires which may be a high-power transmission line or any form of linear conductor. The signaling apparatus includes two antennæ *a* and *b* which are inductively related to the line wire *l* at a distance apart

comparable with the wave lengths of the signaling energy. Connected between the two antennæ are two coils *s* and *t*. The junction *o* of these coils is connected to earth at *e*. The coils *s* and *t* are inductively coupled to the coil *r* which is connected to the sending or receiving apparatus. If the antennæ *a* and *b* are a half-wave length apart, the coils *s* and *t* will be connected as illustrated, so that their effect upon the coil *r*, in response to the signaling energy, is additive. If the antennæ *a* and *b* are some other distance apart, for example, a quarter-wave length, the connections will be correspondingly changed so that their effect shall still be additive. If the high potential present upon the line *l* be sufficient to produce disturbances in the antennæ *a* and *b*, the resulting disturbances in the coils *s* and *t* neutralize one another, and they are conducted to ground without having produced any result in the coil *r*. The sending or receiving apparatus connected to *r* is, therefore, protected from such disturbances.

The apparatus shown in Fig. 2 is similar except that an auto-transformer is used instead of there being a separate coil corresponding to *r*. The sending or receiving apparatus in this form is connected to the leads *g*.

In Fig. 3, a condenser *h* is shown connected across the ends of the divided coil *s*—*t* by means of which the antenna system may be tuned.

A similar condenser is shown in Fig. 4 and, in addition, the connection to the ground is shown as adjustable. If the antennæ *a* and *b* are not any integral number of quarter-wave lengths apart, the effect of this may be compensated by this adjustment.

In Fig. 5, two condensers *h* and *i* are shown, providing a coupling in the place of the coils *s* and *t*. The connection to the sending or receiving apparatus is over the leads *g*.

In Fig. 6, the antennæ *a* and *n* serve for sending while the antennæ *n* and *f* serve for receiving. The coil *s*—*p* connected with the antenna *a* and the coil *t*—*q* connected to the antenna *f* have their middle points *o* connected to earth by a common conductor. The sending apparatus is coupled to

the antenna *a* by means of the coil *d* and the coil *s*—*p*. The receiving apparatus is coupled to the antenna *f* by means of the coil *m* and the coil *t*—*q*. A condenser *w* is placed between the antenna *n* and the coil *q* and an inductance is shunted about the condenser. This combination makes an anti-resonant circuit for the sending frequency, so that the frequency impressed upon the coil *d* will be delivered to the line wire *l* over the antennæ *a* and *n* but will be prevented from reaching the antenna *f*. When disturbances or high potentials are present upon the line wire *l*, the effects which they produce in the coils *s* and *t* are neutralized by the effects produced in the coils *p* and *q*, which, with the connection between the points *o* and the connection including the condenser *w*, affords a short circuited secondary for all frequencies except the sending frequency.

When three antennæ are used, as just explained in connection with Fig. 6, they may be coupled with three different wires corresponding to the three phases of a three-phase transmission line, as illustrated in Fig. 7. When such a connection is used, the points *o*, instead of being grounded by a special conductor, may be connected to the usual lightning-protective device which affords a connection to ground.

The anti-resonant circuit, including the condenser *w*, may be replaced by a condenser connected between the ground connection *o* and the junction of the antennæ *n* and *f*, as shown at *x* in Fig. 8. When the condenser *x* is properly tuned, it will protect the receiving part of the system from current of the frequency used for sending. Beside shunting current of this frequency, this condenser and the coil *q* together can act as an anti-resonant circuit, stopping currents of this frequency.

Current in line wire *l* or in the corresponding wires of Fig. 7, of the frequency intended to actuate the receiving apparatus connected to the coil *m*, will not affect the sending device, because the connection between the middle points *o* of the two coils causes current of this frequency in the coils *s* and *p* to neutralize its effect in coil *d*. In a similar way, high tension or other disturbances on the line wires are neutralized. Even if this neutralization is not complete, the sending apparatus will not be injured, particularly if it consists of the usual vacuum-tube devices.

Although, I have illustrated a number of various forms of my invention, it is to be understood that the invention is capable of being embodied in many other forms and that variations in the details of construction may be made without departing from the spirit thereof, I, therefore, do not intend to

limit the same except as necessitated by the prior art or indicated by the claims.

I claim as my invention:

1. In a radio signaling system, a line wire, a pair of antennæ inductively coupled to said line wire at points corresponding to different phases of the signaling energy, a reactive connection between said antennæ, whereby a neutral point is produced in said connection, and means for maintaining said neutral point at zero potential.

2. In a radio signaling system, a line wire, three antennæ spaced along said line wire at distances which will cause the signaling energy in said antennæ to differ in phase, a connection between the two extreme antennæ and the middle antenna, reactive devices in said connection on each side of said middle antenna, the neutral points of said reactive devices being connected together and to earth, means for impressing signal sending frequency on one of said reactive devices and means associated with the other of said reactive devices tuned to signal receiving energy.

3. In a radio signaling system, a line wire, three antennæ spaced along said line wire at distances which will cause the signaling energy in said antennæ to differ in phase, a connection between the two extreme antennæ and the middle antenna, reactive devices in said connection on each side of said middle antenna, the neutral points of said reactive devices being connected together and to earth, means for impressing signal sending frequency on one of said reactive devices and means associated with the other of said reactive devices tuned to signal receiving energy and means for preventing energy of the signal sending frequency from reaching the last named reactive device.

4. In a radio signaling system, a line wire, three antennæ spaced along said line wire at distances which will cause the signaling energy in said antennæ to differ in phase, a connection between the two extreme antennæ and the middle antenna, reactive devices in said connection on each side of said middle antenna, the neutral points of said reactive devices being connected together and to earth, means for impressing signal sending frequency on one of said reactive devices and means associated with the other of said reactive devices tuned to signal-receiving energy and means including a selective circuit presenting large impedance to the signal-sending frequency and small impedance to other frequencies for preventing energy of the signal-sending frequency from reaching the last named reactive device.

In testimony whereof I affix my signature.

CARL SCHWARZ.
